DESIGN FOR A CONVERTIBLE BLACKBOARD-DESK

Carl E. Meyerhoefer, Brooklyn, N. Y., assignor to
Lewyt Corporation, a corporation of New
York

Application February 3, 1945, Serial No. 117,751

Term of patent 7 years

(Cl. D33—7)

To all whom it may concern:

Be it known that I, Carl E. Meyerhoefer, a citizen of the United States, residing at Brooklyn, in the county of Kings and State of New York, have invented a new, original, and ornamental Design for Convertible Blackboard-Desk, of which the following is a specification, reference being had to the accompanying drawing, forming part thereof, wherein:

Fig. 1 is a perspective view of my new design for convertible blackboard-desk with the blackboard shown raised, as in use; and

Fig. 2 is a perspective view of my convertible blackboard-desk with the blackboard lowered.

I claim:

The ornamental design for a convertible blackboard-desk, as shown.

CARL E. MEYERHOEFER.
